CLAIM

The ornamental design for a smoking article with mouthpiece, as shown and described.

DESCRIPTION

FIG. 1 is a perspective view of a smoking article with mouthpiece showing our new design.

FIG. 2 is a side elevational view thereof; and,

FIG. 3 is a right end elevational view thereof.

The broken lines in the drawings depict environmental
subject matter only that forms no part of the claimed design.

1 Claim, 2 Drawing Sheets See application file for complete search history.
